UNITED STATES PATENT OFFICE

EARL D. McBRIDE, OF OKLAHOMA CITY, OKLAHOMA

ADJUSTABLE FRACTURE FRAME

Application filed September 22, 1930. Serial No. 483,580.

My invention relates to frames for supporting the human body during the period in which fractured bones are healing.

In treating a fractured hip, it is necessary that the fractured member be rigidly supported for a considerable period of time in order that it may heal properly. It has been found impractical in many instances to place the patient in splints or a cast due to the nature of the fracture and due to the fact that the patient must be moved frequently for sanitary reasons. When splints or a cast is used, the fractured member is often displaced in moving the patient.

The objects of my invention are to provide a device of this class which is new, novel, practical and of utility; which will completely support the patient in a comfortable position; which will support the injured member rigidly in a position of internal rotation, extension, and abduction; which will be adjustable to fit any sized person; which will be adjustable for the treatment of various types of fracture; which will permit the patient to be raised and lowered bodily without effort or movement on his part; which will entirely eliminate the use of splints, casts and the like in the treatment of hip, pelvis and leg fractures; which will be simple in operation; which will be strong and durable; and which will be efficient in accomplishing all the purposes for which it is intended.

With these and other objects in view as will more fully appear, my invention consists in the construction, novel features, and combination of parts hereinafter more fully described, pointed out in the claims hereto appended, and illustrated in the accompanying four sheet drawing, of which:

Figure 1 is a perspective view of the frame of the device, with the body supporting member removed;

Fig. 2 is a perspective view of one of the knee and leg supporting brackets attached upon a fragment of one of the frame members;

Fig. 3 is a sectional view taken along the line 3—3 of Fig. 1;

Fig. 4 is a sectional view taken along the line 4—4 of Fig. 3;

Fig. 5 is a plan view of the body supporting member, showing the manner in which it is attached to the frame;

Fig. 6 is a plan view of the body supporting member; and,

Fig. 7 is a sectional view taken along the line 7—7 of Fig. 6.

Like characters of reference designate like parts in all the figures.

It is understood that various changes in the form, proportion, size, shape, weight and other details of construction, within the scope of my invention may be resorted to without departing from the spirit or broad principle of my invention and without sacrificing any of the advantages thereof; and it is also understood that the drawings are to be interpreted as being illustrative and not restrictive.

One practical embodiment of the invention as illustrated in the drawings comprises:

A frame consisting mainly of two angle iron sections 1 and 2. Section 1 has two parallel sides 3 and 4 and one end of each of said sides are attached integrally or rigidly to an upstanding angle iron member. Said members are indicated as 5 and 6 respectively. Section two consists of two parallel sides 7 and 8, two ends 9 and 10, and two parallel downstanding legs 11 and 12 which are attached rigidly at their upper ends to corresponding ends of said sides 7 and 8. Said legs 11 and 12 are spaced apart a sufficient distance to slidably embrace the exterior sides of said upstanding members 5 and 6, and said members 5 and 6 and said legs 11 and 12 are each provided with corresponding elongated through perforations, or slots 13. Said slots 13 receive bolts 14, the tightening of which acts as a means for holding said sections 1 and 2 in desired vertical relation to each other. It may be seen that said slots 13 permit the variance of the vertical distance between said sides 3 and 4 of section 1 and said end 9 of said section 2.

As a means of supporting the torso at various degrees of inclination, I provide as follows:

Resting slidably within the angle of each of said sides 3 and 4 is provided a pair of parallel angle iron shoes 15 and 16 which have their outer ends extending outwardly past the free ends of said sides 3 and 4. The protruding ends of said shoes 15 and 16 are rigidly connected by a cross-member 17. Said sides 3 and 4 and said shoes 15 and 16 are provided correspondingly with slots 18 and said slots 18 are provided with clamp bolts 190

105

110

115

19. Said bolts 19 act as a means of adjustably positioning said shoes 15 and 16 with respect to said sides 3 and 4. Pivotally connected as shown at 20 to the inner ends of said shoes 15 and 16 is provided a substantially rectangular frame 21 having parallel sides 22 and 23 and an end 24. Said frame 21 pivotally supports, at a substantially midpoint, parallel sides 25 of a brace. Said sides 25 are rigidly connected at their free ends by a cross-member 26. The upper edges of said shoes 15 and 16 are notched as shown at 27 and said notches 27 are adapted to receive said cross member 26 of said brace for supporting said frame 21 at various desired degrees of inclination. Said frame 21 supports the upper portion of a body support 28 best seen in Figs. 5 and 6 and which will be more fully described hereinbelow.

20. The ends of said shoes 15 and 16 which lie nearest said end 17 are each provided with an eye 29; and the ends of said sides 7 and 8 of said section 2 which lie nearest said end 10 are each provided with similar eyes 30. Said eyes 29 and 30 are adapted to receive cables 31 for supporting the entire device. Cable 31 in turn may be supported by any desired structure or frame, not shown, but will preferably be threaded through pulleys and attached to a winch so that the entire device and the patient may be raised or lowered at will.

The upper ends of said upstanding members 5 and 6 are each flanged as shown at 32 and each flange is provided with a perforation 33. A vertical rod 34 has its upper end inserted in each of said perforations 33 and extends downwardly to the respective sides 3 or 4 of said section 1. Said rods 34 are rigidly positioned upon said flanges 32 and said sides 3 or 4 as the case may be by brazing, welding or the like. Said rods 34 are each provided with a slidable set collar 35 each of which are adapted to be held in a desired position upon said rods 34 by a set screw 36. Each collar 35 is provided with an eye 37 the office of which is more fully described hereinbelow.

As may best be seen in Fig. 3, a horizontal rod 38 is provided rigidly between said legs 11 and 12 of section 2, and within the angle of said end 9 of said section 2. Said rod 38 is equipped with a pair of slidable set collars 39 and 40 each having an eye 41 thereon. Said collars 39 and 40 are adapted to be held in a desired position upon said rod 38 by set screws 42. A pair of slidable strap iron hooks 43 are provided exteriorly and transversely of said end 9 of said section 2. Each of said hooks are provided with a perforation in their downwardly protruding ends.

Said body support 28 is constructed of some fibrous material such as canvas or the like, and consists of an upper back portion 44 and a lower back portion 45. Said portion 44 at its upper end is provided with a

plurality of straps 46 and centrally of its nether surface is provided with a like plurality of buckles 47. One side edge of said portion 44 is equipped with a plurality of plain straps 48 and its opposite side edge is provided with a like plurality of straps 49, each of said straps 49 bearing a buckle 50. Said lower portion 45 at one side edge is equipped with a plurality of plain straps 51, and at its opposite side edge with a like plurality of straps 52, each of said straps 52 supporting a buckle 53.

In installing said support 28, upon said frame 21, straps 46 are turned back over said end 24 and tightened into said buckles 47. Said straps 48 are bent over said side 22 of frame 21, and straps 49 are bent over side 23 of frame 21, and straps 48 are then tightened into said buckles 50. Straps 51 and 52 are likewise attached together by buckles 53. In this manner it may be seen that said back portions 44 and 45 may be held taut at any desired degree. It may be seen that an indenture 54 is had in each side edge of said support 28 in order to permit the free action of the brace for said frame 21.

At a point directly below said portion 45, said support 28 has a narrow portion as shown at 55, and directly below said narrow portion 55 is provided oppositely extending wide strap portions 56 and 57, each of which at its extreme outer end is attached to straps 58 and 59, respectively. Said portion 55 is adapted to support the pelvis which is that portion of the patient lying just above the hips, and said portions 56 and 57 are adapted to be placed around the pelvis of the patient just below the hips. This is best illustrated in Fig. 5. Straps 58 and 59 are then attached by snaps to said eyes 37 on said set collars 35.

Directly beneath said strap portions 56 and 57, said support 28 is provided with two longitudinally extending parallel portions 60 and 61, each of which at its lower end is provided with a transverse loop through which is inserted slidably a reinforced strap member 62. Said members 62 are each respectively provided at their outer ends with a strap 63 and 64. Said portions 60 and 61 are adapted to extend along the back of the patient's thighs and said members 62 are adapted to be folded over and around each of the thighs at the groin. As may best be seen in Fig. 7 said members 62 each consist of a pliable metal core 101, covered by a fibrous outer cover 102. Said core 101 is provided for preventing said members 62 from twisting and folding when in use. One of the outer ends of said strap 63 is then attached into said eye 41 of said set collar 40 and the other end is provided with a snap hook 65 which is hooked into the perforation in said strap iron hook 43 on said end 9 of said section 2 of the device. In a like manner one end of said

strap 64 is attached to the eye 41 of said set collar 39 and the other end in turn is provided with a snap hook 66 which is hooked into the perforation in the other one of said strap iron hooks 43 on said end 9 of said section 2.

It may be seen that by vertically adjusting said set collars 35, by adjusting the position of said strap iron hooks 43 with reference to said end 9 of said section 2, by adjusting said set collars 39 and 40 with respect to said rod 38, and by tightening or loosening said straps 58, 59, 63 and 64, the patient's hips may be held in a desired position without the use of splints, casts, and the like.

In the description thus far, the means for supporting the body and upper legs of the patient have been disclosed. I will now describe the organization by which the lower legs are supported and by which the spread of the legs may be adjustably controlled.

Slidably disposed transversely upon said end 9 of said section 2, and between said strap iron hooks 43, I provide a second pair of strap iron hooks 67 and 68. Said hooks 67 and 68 each respectively embrace pivotally one end of arms 69 and 70. Said arms 69 and 70 extend horizontally at an angle across the tops of sides 7 and 8 and longitudinally past the axis of said end 10 if extended.

Resting in the angle of the outer end portion of said arm 69 is provided slidably an extension member 71 having an integral downstanding leg portion 72 which in turn is provided with a flange 73 on its extreme lower end. Said portion 71 is held in slidable engagement with said arm 69 by hooks or guides 74 and 75, and is adapted to be held rigidly in desired longitudinal relation with respect to said arm 69 by a set screw 76. A vertical rod 77 is rigidly positioned by welding or the like between the horizontal portion of said extension 71 and said flange 73. Said rod 77 is equipped with a slidable set collar 78 adapted to be held at a desired point on said rod 77 by a set screw 79. Said set collar 78 is provided with an eye 80. A screw clamp 81 is provided on said side 7 of said section 2, and over said arm 69, and acts as a means for holding said arm 69 at a desired angle with respect to said side 7.

Said arm 70 is likewise provided with an extension 82, downstanding leg 83, flange 84, rod 85, set collar 86 and clamp 87, similar in form to said extension 71, leg 72, flange 73, rod 77, set collar 78 and clamp 81 on said arm 69.

Slidably disposed upon the midportion of said arm 70 is a vertical standard 88, best seen in Fig. 2. A clamp 89 embraces the upper portion of said standard 88, and also slidably embraces a horizontal arm 90 having a strap iron hook 91 thereon. Said clamp 89 may be held at a desired vertical position by the tightening of a set screw 92. Said

arm 69 is also provided with a standard 88, clamp 89 and arm 90 similar to those provided on said arm 70. It will be understood, however, that the arms 90 both extend toward the center of section 2 and toward each other.

Said hooks 91 and their supporting mechanism are provided for the purpose of receiving a strap or the like, not shown, for supporting the patient's knees. Said standards 88 may be slid along said arms 69 and 70 so as to fit various sized patients, and said arms 90 may be slid to a desired position within clamps 89 so as to hold the knees in a desired spaced relation. Said clamps 89 also make it possible to hold the patient's knees at a desired height. Said set collars 78 and 86 are provided for the purpose of receiving straps, not shown, for supporting the patient's lower legs at the ankles. The height at which the lower legs are held may be adjusted by varying the vertical position of said collars 78 and 86 respectively upon said vertical rods 77 and 85. It may also be seen that by varying the longitudinal relation of said extensions 71 and 82 respectively with respect to said arms 69 and 70, that the length of the patient's legs may be accommodated.

For cases in which it is found desirable to retain the patient's lower legs at a point below the lower ends of said legs 72 and 83, each of said legs are provided with a slideable extension 99 having a flange 100, similar in office to said flanges 73 and 84 on said legs 72 and 83.

As a means of supporting the outer ends of said arms 69 and 70, said end 10 of section 2 is provided with two extension members 93 and 94 which rests upon the top of said end 10 and are held in slidable engagement therewith by laterally extending lugs 95, 96, 97 and 98 which are bent around the edges of said end 10.

As the purpose and function of each portion of the device has been described herein as the structure was described, it is not believed necessary to further describe the operation of the device. It may be seen that means have been shown for adjustably supporting a patient's torso, hips, upper legs, knees, and lower legs. Also that a means for positioning the legs with respect to each other has been provided, and that the patient may be raised or lowered at will without effort on his part, and without otherwise moving his legs.

Obviously, the invention is susceptible of embodiment in forms other than those which are illustrated in the accompanying drawings and described herein, and applicable for uses and purposes other than as detailed, and I therefore consider as my own all such modifications and adaptations and other uses of the form of the device herein described as fairly fall within the scope of my invention.

Having thus described my invention, what

is claimed and desired to be secured by Letters Patent, is:

1. A device of the class described, embodying a substantially rectangular frame comprising a first and second section, said sections lying on two different horizontal planes with one end of the first section below and in a vertical plane with the opposite end of the second section, said ends having vertical connection at each of their sides, means for adjusting the vertical distance between said connected ends, said first section bearing a longitudinally adjustable body supporting frame adapted for disposition at various angles of inclination, means carried by said second section for supporting a patient's hips and upper legs adjustably as to height, tortion, and spread, means carried by said second section for supporting the patient's knees adjustably as to height and spread, and means also carried by said second section for supporting the patient's lower legs adjustably as to height and spread.

2. A device, of the class described, embodying a substantially rectangular metal frame comprising a first and second section, said sections lying on two different horizontal planes with one end of the first section below and in a vertical plane with the opposite end of the second section, said ends having vertical connection at each of their sides, means for adjusting the vertical distance between said connected ends, said first section bearing a longitudinally adjustable body supporting frame adapted for disposition at various angles of inclination, said frame bearing a fibrous sheet having suitable straps on its edges for attaching it thereto, means carried by said second section for supporting a patient's hips and upper legs adjustably as to height, tortion, and spread, means carried by said second section for supporting the patient's knees adjustably as to height and spread, and means also carried by said second section for supporting the patient's lower legs adjustably as to height and spread.

3. Organization as described in claim 2, in which the means for adjusting the longitudinal position of said body support, comprises corresponding elongated slots in the sides of said first section and in said body supporting frame, and bolts through said slots for holding said body supporting frame upon said sides.

4. Organization as described in claim 2, in which said adjustable hip supporting means comprises a vertical rod carried by each vertical member connecting said two sections, a set collar slidably mounted upon each rod, adapted to receive straps connected to said fibrous sheet, a horizontal rod carried between the ends of the sides of said

second section, a pair of slideable set collars carried by said horizontal rod and adapted to attach other straps connected to said fibrous sheet, and a pair of hooks slidably mounted on a cross member between the ends of the sides of said second section and adapted to attach to still other straps connected to said fibrous sheet.

5. Organization as described in claim 2, in which said knee supporting means comprises a pair of horizontal arms pivoted at one end to a cross member between the ends of the sides of said second section, their outer ends extending at an angle over the sides of said second section and past its outer end, a clamp for positioning each of said arms upon said sides, a vertical standard slidably mounted medially on each of said arms, a clamp slidably mounted on each of said standards, a horizontal member slidably embraced in each of said clamps, and a hook carried by each of said horizontal members, said hooks each adapted to attach a strap for supporting the patient's knees.

6. In a fracture frame for supporting a human body in various positions, the combination with the portion of said frame for supporting the torso of said body at various degrees of inclination, of a fibrous sheet having suitable straps on its edges for attaching it to said frame, a narrow portion for supporting the lower back of said body above the hips, a wider portion for supporting the hips, straps connected to the opposite edges of said wider portion for passing around the hips and loins of said body, two parallel, longitudinally extending strips, each for extending along the back of one upper leg, and a pair of padded straps each attached transversely to the end of one of said strips, said padded straps each for encircling the upper portion of one leg and holding said body against longitudinal movement with respect to said frame.

7. Organization as described in claim 2 in which said sheet comprises a substantially rectangular portion adapted for suspension by said straps within said frame, said sheet having a narrow portion for supporting the lower back of said body above the hips, a wider portion for supporting the hips, strap connected to the opposite edges of said wider portion for passing around the hips and loins of said body, two parallel, longitudinally extending strips, each for extending along the back of one upper leg, and a pair of padded straps each attached transversely to the end of one of said strips, said padded straps each for encircling the upper portion of one leg and holding said body against longitudinal movement with respect to said frame.

EARL D. McBRIDE.
